Patented Feb. 16, 1858

H. Hartman & T. Polkman,
Design for a Spoon,
New York

1857

Henry Hebbard & John Polhamus, of New York, N.Y.

Letters Patent No. 988. Dated Feby. 16th 1858.

The schedule referred to in these Letters Patent is making part of the same.

To all whom it may concern:

Be it known that we, Henry Hebbard

and John Polhamus, of the City, County and State of New York, have produced a new and original design for ornamenting the handles of Spoons, Forks, &c. and they do hereby declare the following to be a full description of the same, reference being had to the accompanying drawings forming part of this specification the same letters of reference wherever they occur referring to like parts.

Figure 1. is the front side of the spoon.

" 2. is the reverse side of the spoon.

On the front side of the handle of the spoon is a raised thread a. extending entirely around the margin of the handle, and terminating at the shank in a scroll b. having a three lobed leaf c. between its sides and extending upwards on the handle of the spoon. On the raised or oval shaped center d. between the marginal threads, at the head of the handle is a shield e. surrounded by a heavy raised border f. having on its inner edge a fine marginal raised thread g. This shield is of an oval form, having at its head a scroll h. encircling the border f. and a five lobed leaf i. the point of which extends down towards the middle of the shield. Encircling the lower end of the oval border, is also another scroll j. between the sides of which extend a five lobed leaf k. like the one at the head of the shield,

though larger, and having its point extending down between the marginal threads on the handle upon the oval or rounded center ^d, and thereby completing the ornamental device for the front of the spoon.

On the back of the handle of the spoon there are the same devices as are used to ornament the front side of the handle, except at the heel ^m of the spoon, which is covered by a scroll ⁿ supporting a five lobed leaf ^p, of the same pattern as those used in ornamenting the front of the handle of the spoon.

It will be seen that the scroll and leaf are blended together, so as to form apparently an entire figure of a leaf, but as Flora has no such graceful twinings of the stems of leaves and it is only exhibited in the myth of the designer, its peculiarity becomes the distinguishing feature from all other designs where leaves have been used for similar purposes; and in combination with the marginal thread of the handle and heavy raised oval border of the shield forms the nature of the invention for which a patent is desired.

Exd S.M.P. What we claim therefore is the use of the combination of the scroll leaf, with the single marginal thread & heavy raised oval border for the shield plate, substantially as described for ornamenting the handles of spoons, forks and other articles.
